HAIR WAVING APPARATUS

William G. Shelton, St. Louis, Mo.; Richard T. Shelton, Lester E. Sherwood and Mississippi Valley Trust Company, St. Louis, Mo., executors of said William G. Shelton, deceased, assignors to W. G. Shelton Company, St. Louis, Mo., a corporation of Missouri

Application July 3, 1933, Serial No. 678,755

8 Claims. (Cl. 132—33)

This invention relates to the hair waving art and consists particularly in novel protector clamp apparatus for use in permanent waving.

In applying a so-called permanent wave to the hair, it is customary to secure a protector clamp device near the base of the tress before winding upon the curling rod, either from the outer extremity inwardly as in the case of croquignole waving, or from the scalp outwardly as in the case of corkscrew waving. The protector clamp serves to prevent discomfort to the scalp due to pulling of individual strands during winding, and also serves to protect the scalp from heat, steam and drops of hot liquid escaping from the heater which is applied over the wound strand to effect the change in structure of the hair resulting in a wave which will hold its shape for a substantial period of time.

Present types of protector clamps usually comprise pivoted jaws which close about the strand, the undersurface of the jaws as well as the hair engaging edges thereof being frequently padded with a pliable material such as felt or rubber. The jaws thus in the closed position yieldingly and firmly engage the hair, but particularly in the case of croquignole waving, in which the hair has heretofore been wound in flat strands, crevices are apt to exist between the jaws immediately adjacent the edges of the inclosed strand through which crevices steam and moisture may leak. Moreover, stray strands of the hair may become entangled in the pivotal connection of the jaws, in the latch usually provided at the free end, or in other appurtenances with which the clamp is usually provided.

In a co-pending application, Serial No. 671,815, filed May 19, 1933 in the name of the present inventor, is illustrated a protector clamp device, particularly intended for croquignole waving, comprising pivoted jaws with registering V-shaped recesses which are disposed to inclose a pair of pencil-shaped tresses, spring impelled levers yieldingly engaging the tresses to insure snug gripping of the same. Felt pads are provided on the bottom of the jaws adjacent the scalp, and seats at each end of the device serve to seat the curling rod in a position paralleling the jaws.

One object of the present invention is to provide protector clamp apparatus, for gripping the hair in pencil-shaped tresses, which will be simpler than the device illustrated in the above-mentioned co-pending application, while at the same time being arranged to effectively inclose

the hair without leaving undesirable crevices between the jaws.

Another object is to provide apparatus of the above type in which means are provided for confining all of the strands of the segregated tress, 60 during application of the clamping device, to eliminate the possibility of stray strands becoming entangled in the hinge, latch, or other parts of the clamp.

Another object is to provide a device of the 65 above type in which the less durable portions, such as the padding applied to the undersurfaces and hair engaging edges of the jaws, may be readily renewed without the necessity of renewing the more expensive clamping portions of the appa- 70 ratus.

Another object is to provide a protector clamp 75 for use in croquignole waving which is adapted to more snugly grip the hair than previous devices used for a similar purpose.

These objects and others hereafter appearing are attained substantially by my novel apparatus in which is provided separate protector and clamping members, the protector member comprising a pad of pliable material, such as rubber, 80 having one or more perforated projections for receiving segregated tresses, and the clamp comprising pivoted jaws with registering recesses arranged to close about the projecting parts of the protector member to cause the same to snugly 85 grip the contained tresses.

In the accompanying drawing which illustrates the invention—

Figure 1 is a side view of the protector member and a curling rod applied to the hair. 90

Figure 2 is a top view of the protector member.

Figure 3 is a detail section on the line 3—3 of Figure 2.

Figure 4 is a top view of the clamp member.

Figure 5 is a top view of the protector and 95 clamp members assembled and applied to segregated tresses.

Figure 6 is a transverse sectional view on the line 6—6 of Figure 5.

Figure 7 is a side view of the assembled pro- 100 tector and clamping members.

The apparatus illustrated comprises broadly a protector member 1, preferably of rubber or similar pliable material, and a clamping member 2 which are applied to the base of the hair before the tresses are wound about the curling rod 3, of familiar form, including a pivoted clip 4 for securing the end of the hair to the rod, trunnion 5 at one end, and a ratchet 6, trunnion 7a and manipulating handle 7 at the other end. 105

110

The protector member is formed of a relatively broad, flat base or body portion 8, having spaced tubular projections 9, shouldered at 10, and with central perforations 9a for receiving the pencil-shaped tresses S. Base portion 8 and projections 9 are split as at 11 and 11a to permit the tresses to be introduced from the side into the perforated projections 9.

The clamping member comprises a pair of jaws 12 and 13, pivoted at one end as at 14, one of the jaws being provided at the free end with a latch 15 for engaging a seat 16 in the free end of the other jaw. Jaw 12 is of U-section including walls 17 and 18, the hair engaging edges thereof being recessed at 19. Angle projection 20 on latch 15 and a cradle 21 at the opposite end of jaw 12 are provided for engaging trunnions 5 and 7a to properly seat the curling rod in a position parallelizing the jaws, and a spring pawl 22 is disposed to cooperate with ratchet 6 on the curling rod to prevent loosening of the hair.

Jaw 13 is formed of a metal sheet with recesses 23 in the hair engaging edge thereof corresponding to the recesses 19 in the jaw 12. The recesses 25 19 and 23 in the jaws 12 and 13 are rounded at the bottom and these recesses are disposed to overlap when the jaws are swung together.

In forming a wave with the use of the novel apparatus, the hair is first divided into pencil-shaped strands, as in Figures 1, 2 and 5, and adjacent tresses are slipped through the slits 11 in the pliable protector member into the perforated projections 9. The protector member is drawn as closely as possible to the scalp and the clamping member applied. When the jaws are secured together by means of latch 15, the recesses 19 and 23 will cooperate to snugly inclose the projections 9 between base portion 8 and shoulders 10, and the pliable projections will be compressed in a manner to closely grip the tresses S, as clearly shown in Figure 6.

The ends of the pair of tresses gripped by the protector may then be secured to a rod, such as 3 in Figure 1, and the tresses wound spirally towards the scalp to form the croquignole wave. The rod is seated and tightened against the clamping member and a suitable heater applied over the wound hair in a familiar manner.

If desired, the pliable protector member and clamp may be arranged for receiving one or more than two tresses. The apparatus may be used in forming corkscrew type of wave in which the hair is wound from the scalp outwardly about a curling rod. In such case, the rod may be perpendicularly secured to the clamp member, as illustrated in Patent #1,884,305, issued to the present inventor. It would also be within the spirit of the invention to eliminate the body portion 8 which connects the tubular projections 9, tubular members such as the projections 9 being separately applied to the hair before application of the clamp. The undersurface of the clamp may or may not be provided with suitable padding. Also the base portion of the protector member may be formed of a different material than the projections 9, such as felt, it being only necessary that the tubular projections be sufficiently pliable to permit their deformation by the clamp in a manner to snugly grip the hair.

The apparatus illustrated may be otherwise modified as will occur to those skilled in the art, and exclusive use of all such modifications as come within the scope of the appended claims is contemplated.

What is claimed is:

1. In apparatus of the class described, a member of pliable material having a perforated projection for receiving a tress, said member being split to facilitate insertion of the hair into said perforated projection, and a clamp shaped to grip said projection to cause the same to snugly enclose the contained tress.

2. A protector of pliable material for use in hair waving comprising a base portion for application adjacent the head and a plurality of perforated tubular projections, said base portion and said projections being split to permit insertion of tresses into said perforated projections from the side.

3. In apparatus of the class described, a protector of pliable material including a base portion for application immediately adjacent the head and a plurality of perforated projections for receiving segregated tresses, and a clamp including relatively movable jaws recessed to close about said projections and cause the same to snugly grip the contained tresses.

4. In apparatus of the class described, a protector of pliable material including a perforated projection for receiving a segregated tress, and a clamp including relatively movable jaws shaped to snugly grip said projection and an element for engaging a curling rod to maintain the same properly positioned relative to said clamp.

5. In apparatus of the class described, perforated tubular elements of pliable material for receiving segregated pencil-shaped tresses, and a clamp including elongated jaws with transverse recesses shaped to close about said elements to cause the same to snugly grip the contained tresses and means for supporting a curling rod in a position parallel to said jaws.

6. In apparatus of the class described, a one-piece protector member of pliable material and with a perforation to receive a segregated tress, said member being split to permit insertion of a tress into said perforation from the side, and a clamp with concavely recessed jaws shaped to engage the portion of said protector member adjacent said perforation to cause said member to snugly inclose the contained tress.

7. In apparatus of the class described, a clamp member comprising rigid jaws hinged together at one end and provided with a securing device at the other end, there being aligned transverse V cuts in said elements intermediate the ends of the clamp, and a hair engaging element for use with said clamp comprising a flat sheet of material corresponding in shape and area to said clamp and provided with upstanding hair receiving hollow projections positioned to be seated in said recesses and constricted by said clamp.

8. In apparatus of the class described, a hair engaging member comprising a flat slab of rubber slit from each end inwardly a substantial distance, there being an upstanding tubular projection at the inner end of each slit, the sides of which projections are also slit to permit lateral insertion of strands of hair to the interior thereof, and a cooperating clamp member comprising a pair of plates hinged together at one end and provided with securing means at the other end and having opposed V-shaped cuts intermediate said ends for receiving said projections and gradually contracting the same as said clamp is tightened.

WILLIAM G. SHELTON.
